LOOP-TAKER MECHANISM FOR SEWING MACHINES

Walter Myers, Bridgeport, Conn., assignor to The Singer Manufacturing Company, Elizabeth, N. J., a corporation of New Jersey

Application October 14, 1939, Serial No. 299,415

12 Claims. (Cl. 112—184)

This invention relates to loop-taker mechanisms for sewing machines and more particularly to loop-taker mechanisms of the vertical-axis rotary hook type in which a bobbin-carrier is journaled in and restrained against rotation with the rotary hook.

A primary object of the invention is to provide bobbin-carrier rotation restraining means which will facilitate casting of needle-thread loops about the bobbin-carrier by the rotary hook and permit of operation of the sewing machine at high speeds.

A further object of the invention is to provide a rotary-hook mechanism assembly adapted to be detachably secured as a unit to a sewing machine and including improved bobbin-carrier rotation restraining means.

With these and other objects in view, as will hereinafter appear, the invention consists in the loop-taker mechanism described in connection with the accompanying drawings which illustrate a preferred embodiment of the invention and in which:

Fig. 1 represents a vertical section of the loop-taker end portion of the bed-plate of a two-needle sewing machine containing the present improvements, the left hand loop-taker mechanism being shown in vertical section and the right hand loop-taker mechanism mainly in front elevation. Fig. 2 is a bottom plan view and Fig. 3 a top plan view of the same portion of the machine, the throat-plate and side slide-plates being removed in Fig. 3. Fig. 4 is a top plan view of the loop-taker-mechanism supporting bracket, and Fig. 5 represents a vertical section of said bracket substantially on the line 3—5 of Fig. 4. Figs. 6 and 7 represent different perspective views of the bobbin-carrier. Fig. 8 is an enlarged vertical section of portions of one of the loop-takers and its bobbin-carrier, the section being taken substantially on the line 8—8 of Fig. 3.

The sewing machine shown in the drawings has a work-supporting bed-plate 1 provided with the usual side slide-plates 2 and 3, front slide-plate 4 and throat-plate 5.

Operating through suitable feed-slots in the throat-plate 5 is a feed-dog 6 carried by a feed-bar 7 deriving work-advancing movements from a horizontally disposed feed-advance rock-shaft 8. The rock-shaft 8 is journaled in split bushings 9 and 10, respectively clamped by set-screws 11 in spaced bearing-lugs 12 and 13 depending from the bed-plate 1, the set-screws 11 being

secured by screws 14. The bushing-aperture in the bearing-lug 13 is larger than the bushing-aperture in the bearing-lug 12 and the bushing 10 is correspondingly larger than the bushing 9 to accommodate the rock-shaft 8 of uniform diameter. The shaft-bearing arrangement described facilitates manufacture and particularly when it is desired to provide several alined shaft-bearings, the split-bushings providing for taking up wear.

The feed-bar 7 has at its rearward end a fork 7' engaged by an eccentric 15 carried by a horizontally disposed rotary shaft 16 journaled in bushings 17 and 18 which are respectively secured in bearing-lugs 19 and 20 depending from the bed-plate 1.

The feed-dog 6 has needle-apertures 21 to receive the two needles 22 carried by a needle-bar 23, said needle-bar being actuated by means of 20 needle-reciprocating and vibrating mechanism (not shown) which, in the present machine, is substantially the same as that disclosed in my prior U. S. Patent No. 2,128,031, Aug. 23, 1938. Opposed to the feed-dog 6 is the usual spring-depressed presser-foot 24.

Complemental to the needles 22 in the formation of lock-stitches are two corresponding loop-takers of the vertical-axis rotary hook type disposed at opposite sides of the feed-bar 7. Each of the loop-taker mechanisms, including thread-case rotation restraining means, is assembled as a complete unit in a supporting-bracket 25 or 26 commercially known as a hook-saddle. Each bracket 25 or 26 has a rearwardly extending split boss 27 clamped by a screw 28 upon a bearing-bushing of the rotary shaft 16, the boss of the supporting-bracket 25 being clamped upon the bushing 17 and the boss of the supporting-bracket 26 being clamped upon the bushing 18. Each supporting-bracket 25 or 26 also has a forwardly extending and slotted lug 29 adjustably secured by a screw 30 to a rib 31 at the under side of the bed-plate 1. As the loop-taker mechanisms of the two supporting-brackets are the same, the description of one will suffice.

The supporting-bracket 25 has vertically spaced bearing-lugs 32 and 33, provided with vertically alined apertures 34 and 35, the lower portions of which apertures are threaded. Disposed in the upper unthreaded portions of the apertures 34 and 35 are ball-bearings 36 and 37 which are vertically located in said apertures by bushings 38 and 39 threaded into the lugs 32 and 33, respectively, from the under sides of said lugs.

Rotatably journaled in the ball-bearings 36, 37, is a vertically disposed rotary-hook shaft 40, and secured to said shaft for rotation therewith is a spiral gear 41 driven by a spiral gear 42 secured upon the rotary-hook and feed-lift actuating shaft 16, said gears being proportioned so that the hook-shaft 40 rotates twice for each rotation of the actuating shaft 16.

The rotary-hook shaft 40 has a longitudinal bore 43 enlarged at the lower end of said shaft to receive the reduced stem of an eccentric 44 disposed below the supporting bracket 25. The eccentric 44 is secured for rotation with the hook-shaft 40, by means of a pin 45 extending transversely through the stem of the eccentric 44 and entering suitable notches in the lower end of the hook-shaft. Threaded into the upper end of the stem of the eccentric 44 is an elongated screw 46 extending downwardly through the bore 43 of the hook-shaft and serving to hold the hook-shaft 40 and the eccentric 44 in assembled relationship.

Integral with the upper end of the hook-shaft 40 is the cup-shaped body of a rotary hook 47, and interposed between the bottom wall of said rotary hook and the upper ball-bearing 36 is a shouldered washer 48 providing at the under side thereof a recess in which is disposed a washer 49 of felt or other similar material and overlying the race-rings of the ball-bearing 36. Similar washers, indicated in the drawings by the same reference characters, are interposed between the hook-shaft gear 40 and the lower ball-bearing 37. While the rotary hook 47 is, in the present case, integral with the hook-shaft 40, it will of course be understood that the rotary-hook may comprise a separate body secured to the hook-shaft in any usual manner, or it may be secured to the hook-shaft by the screw 46.

The side wall of the cup-shaped body of the rotary hook 47 is partly cut away to provide a loop-seizing beak 50, and a needle-guard member 51 is detachably secured upon the side wall of the rotary hook to extend across the gap of said cutaway portion and under the beak of the hook.

The inner face of the hook-body, within the rim thereof, is shouldered to provide a bobbin-carrier raceway comprising a vertically cylindrical bearing wall 52 and an inwardly extending bearing ledge 53. Journaled in said raceway is an interrupted bearing-rib 54 of a bobbin-carrier 55, said bearing-rib 54 being retained in the hook-raceway by a gib 56 secured by screws 57 upon the hook-rim. The gib is shaped substantially the same as that more fully disclosed in my prior U. S. Patent No. 1,917,771, July 11, 1933, although it is preferably made in two end-to-end abutting sections. One end of the interrupted bearing-rib 54 of the bobbin-carrier provides an inclined thread-loop detaining shoulder 58.

The bobbin-carrier 55 has an interrupted peripheral flange 59 overhanging the hook-gib 56, which flange has a beveled or inclined portion 59' at the thread-loop cast-on side of the bobbin-carrier directly above the end portion of the bearing-rib 54 which terminates in the shoulder 58. Adjacent its opposite end, the flange 59 of the bobbin-carrier is provided with an upwardly open segmental oil-pocket 60 preferably containing an oil-absorbent material 61. As shown in Fig. 8 of the drawings, the bottom wall of the oil-pocket 60 is connected by a vertical duct 62 in the side wall of the bobbin-carrier with a radial duct 63

terminating in the outer face of the bearing-rib 54, thereby providing means for supplying lubricant to the thread-carrier raceway.

The bobbin-carrier flange 59 is partly cut away in the portion thereof substantially opposite to the bearing-rib and flange gaps to provide a shouldered recess 64. Secured by screws 65 to the outer face of the vertical side wall of the recess 64 is a bobbin-thread tension-spring 66 bearing against said side wall between two thread-slits 67 and 68 in the bobbin-carrier side wall. The bobbin-carrier 55 has the usual bobbin-post 69 rising from the bobbin-carrier bottom wall, and pivoted to said post 69 is the usual spring-pressed latch-member 70 having its free end adapted to enter a recess 71 in the rim of the bobbin-carrier 55, whereby the latch-member 70 in its closed or bobbin-retaining position is flush with the rim of the bobbin-carrier. Substantially opposite to the latch-recess 71, the inner edge of the bobbin-carrier rim is partly cut away to provide a finger-notch 72 facilitating removal of the bobbin 73 when the latch-member 70 has been opened.

When threading the bobbin-carrier, the bobbin-thread is passed outwardly from the bobbin 73 through the thread-slit 67, under the tension-spring 66, and inwardly through the thread-slit 68, from which the bobbin-thread then passes across the upper flange of the bobbin 73 to the needle-aperture 21 in the feed-dog 6.

The bobbin-carrier 55 is restrained against rotation with the rotary hook 47 by an escapement device permitting free passage of the needle-thread loops about the bobbin-carrier. To this end, the bobbin-carrier flange 59 is provided at substantially diametrically opposite sides of the bobbin-carrier with two horizontally arcuate apertures 74 adapted to be entered by opposed and horizontally arcuate fingers 75 of a rocking escapement-yoke 76. The escapement-finger receiving apertures 74 of the bobbin-carrier flange 59 are formed within the vertical thickness of said flange, whereby the rim of the bobbin-carrier presents a smooth and unbroken surface above the upwardly closed apertures to the passage of the needle-thread loops.

The escapement-yoke 76 is secured by screws 77 and locating-pins 78 upon the upper end of an enlarged head 79 of a vertically disposed escapement rock-shaft 80, the head 79 being partly cut away at one side thereof to provide clearance for the rotary hook 47. The rock-shaft 80 is journaled in a slightly eccentric vertical aperture 81 of a bushing 82 adjustably secured by a set-screw 83 in a vertical aperture 84 provided in the supporting-bracket 25. The head 79 of the rock-shaft 80 is smaller in diameter than the bracket-aperture 84 and rests upon the upper end of the bushing 82. As the bushing 82 terminates below the upper end of the bracket-aperture 84, the latter thereby provides an oil-recess above the bushing 82. The squared lower end 82' of the bushing 82 extends slightly below the supporting-bracket 25, whereby the bushing 82 may be turned to properly position the escapement-fingers 75 with respect to the bobbin-carrier escapement-apertures 74.

The escapement rock-shaft 80 extends below the bushing 82, and clamped to the lower end of said rock-shaft by a screw 85 is the split hub of a horizontally disposed crank-arm 86. The crank-arm 86 is forked at its free end to embrace the eccentric 44 secured for rotation with the hook-shaft 40. It will therefore be understood that

the escapement-yoke fingers 75 alternately engage the bobbin-carrier 55 in each rotation of the rotary hook 47, the operation of said fingers being timed to provide a free passage of the needle-thread loops about the bobbin-carrier.

Detachably secured by screws 87 to the flattened lower face of each supporting-bracket 25 or 26, is a casing 88 which houses the hook-shaft eccentric and the crank-arm actuated thereby, said casing also functioning to collect lubricant escaping from the lower hook-shaft bearing and from the escapement rock-shaft, whereby the actuating mechanism housed by said casing is adequately lubricated.

As illustrated in Figs. 4 and 5 of the drawings, the supporting-bracket 26 has a vertical oil-well aperture 89 disposed adjacent the bracket-lugs 32, 33, and the upper face of said bracket is provided with oil-conducting grooves 90 and 91. The groove 90 connects the upper end of the oil-well 89 and the felt-washer 49 overlying the upper ball-bearing 36, and the groove 91 connects the oil-well 89 and the bracket-aperture 84 above the bushing 82 therein. The oil-well 89 is also connected, adjacent its lower end and by an oil-duct 92, with the felt-washer 49 overlying the lower ball-bearing 37. The described arrangement provides for supplying lubricant to the hook-shaft bearings 36, 37, and to the bearing of the escapement rock-shaft 80. As above mentioned, any excess oil escaping from the lower hook-shaft bearing 37 and from the bearing of the rock-shaft 80 is collected by the casing 88. The supporting bracket 25 is provided in the same manner with means for lubricating the hook-shaft and the escapement rock-shaft journaled therein.

Having thus set forth the nature of the invention what I claim herein is:

1. Stitch-forming mechanism for sewing machines comprising, a vertically reciprocatory needle, a vertical-axis rotary hook having a bobbin-carrier raceway, a bobbin-carrier having a bearing-rib journaled in said raceway and about which bobbin-carrier the needle-thread loops are cast by said rotary hook, said bobbin-carrier having a flange overhanging said bearing-rib and provided at opposite sides of the bobbin-carrier within the thickness of said flange with substantially horizontal and upwardly closed escapement-apertures, a vertical-axis yoke having escapement-fingers adapted alternately to enter the respective escapement-apertures of the bobbin-carrier flange, and means for actuating said yoke in timed relation with respect to the rotation of the rotary hook to provide a free passage for the needle-thread loops.

2. Stitch-forming mechanism for sewing machines comprising, a vertically reciprocatory needle, a rotary hook having a bobbin-carrier raceway, a vertically disposed rotary-hook carrying shaft, means for rotating said shaft, a bobbin-carrier journaled in said raceway and provided in opposite sides thereof with substantially horizontal escapement-apertures, said bobbin-carrier having an upper rim presenting a smooth and unbroken surface above said apertures, a vertical-axis rock-shaft disposed adjacent to said hook-shaft, a yoke carried by the upper end of said rock-shaft and having escapement-fingers adapted alternately to enter the respective escapement-apertures of the bobbin-carrier, an eccentric carried by the lower end of said rotary hook-shaft, and a crank-arm extending

from said rock-shaft and having a fork engaging said eccentric.

3. A rotary-hook mechanism assembly adapted to be detachably secured as a unit to a sewing machine, comprising, a supporting bracket having spaced bearing-lugs, a rotary-hook shaft journaled in said bearing-lugs, a spiral-gear carried by said hook-shaft between said bearing-lugs, a rotary hook carried by said hook-shaft, a bobbin-carrier journaled in said rotary hook and provided with a pair of escapement-apertures, an escapement yoke supported by said bracket for rocking movements about an axis substantially parallel to the axis of rotation of said hook-shaft, said yoke having escapement-fingers adapted alternately to enter the respective escapement-apertures of the bobbin-carrier, and means operatively connected to said hook-shaft for actuating said escapement-yoke.

4. A rotary-hook mechanism assembly adapted to be detachably secured as a unit to a sewing machine, comprising, a supporting bracket, a rotary-hook shaft journaled in said bracket, a spiral-gear carried by said hook-shaft, a rotary hook carried by one end of said shaft, an eccentric carried by the other end of said shaft, a bobbin-carrier journaled in said rotary hook and provided with a pair of escapement-apertures, a rock-shaft journaled in said bracket and disposed substantially parallel to said rotary-hook-shaft, a yoke carried by one end of said rock-shaft and having escapement-fingers adapted alternately to enter the respective escapement-apertures of said bobbin-carrier, a crank-arm extending from said rock-shaft and having a fork engaging said eccentric, and a casing detachably secured to said supporting bracket and housing said eccentric and crank-arm.

5. A rotary-hook mechanism assembly adapted to be detachably secured as a unit to the frame of a sewing machine, comprising, a supporting bracket having spaced bearing-lugs, a rotary-hook shaft journaled in said bearing-lugs, a gear-wheel carried by said hook-shaft between said bearing-lugs, a rotary hook carried by said hook-shaft at one side of said bracket, an eccentric carried by said hook-shaft at the opposite side of said bracket, a bobbin-carrier journaled in said rotary hook, a rock-shaft journaled in said bracket and disposed substantially parallel to said hook-shaft, an escapement-yoke carried by one end of said rock-shaft and providing escapement-fingers adapted alternately to engage said bobbin-carrier for restraining the bobbin-carrier against rotation with said rotary hook, a crank-arm extending from the other end of said rock-shaft and in operative engagement with said eccentric for actuating said rock-shaft, and a casing detachably secured to said supporting bracket and housing said eccentric and crank-arm.

6. A rotary-hook mechanism assembly adapted to be detachably secured as a unit to a sewing machine, comprising, a supporting bracket, a rotary-hook shaft journaled in said bracket, a gear-wheel carried by said shaft, a rotary hook carried by said shaft at one side of said bracket, an escapement-actuating eccentric carried by said shaft at the opposite side of said bracket, a bobbin-carrier journaled in said rotary hook, a rock-shaft journaled in said bracket, an escapement-yoke carried by said rock-shaft at the rotary hook side of said bracket, said yoke providing escapement-fingers adapted alternately to engage said bobbin-carrier for restraining the bobbin-carrier

against rotation with said rotary hook, a crank-arm carried by said rock-shaft and in operative engagement with said eccentric for actuating said rock-shaft, and a casing detachably secured to said supporting bracket and housing said eccentric and crank-arm.

7. A rotary-hook mechanism assembly adapted to be detachably secured as a unit to a sewing machine, comprising, a supporting bracket, a rotary-hook shaft journaled in said bracket, a gear-wheel carried by said shaft, a rotary hook carried by said shaft, a bobbin-carrier journaled in said rotary hook, a rocking yoke having escapement-fingers adapted alternately to engage said bobbin-carrier for restraining the bobbin-carrier against rotation with said rotary hook, means for rocking said yoke, and means providing for lateral adjustment of the rocking axis of said yoke.

8. A rotary-hook mechanism assembly adapted to be detachably secured as a unit to a sewing machine, comprising, a supporting bracket, a rotary-hook shaft journaled in said bracket, a rotary hook carried by said shaft, a bobbin-carrier journaled in said rotary hook, an eccentrically apertured bushing secured in said bracket for turning adjustment, a rock-shaft journaled in the eccentric aperture of said bushing, a yoke carried by said rock-shaft and having escapement-fingers adapted alternately to engage said bobbin-carrier for restraining the bobbin-carrier against rotation with said rotary hook, and operative connections with said rotary-hook shaft for actuating said rock-shaft.

9. A rotary-hook mechanism assembly adapted to be detachably secured as a unit to a sewing machine, comprising, a supporting bracket having substantially parallel bearing-apertures, a hook-shaft rotatably journaled in one of said bearing-apertures, a rotary hook carried by said shaft, an eccentric carried by said shaft, a bobbin-carrier journaled in said rotary hook, a bushing secured in the other of said bracket-apertures for turning adjustment therein, said bushing having a shaft-bearing aperture eccentric to the bushing-receiving aperture of said bracket, a rock-shaft journaled in the eccentric aperture of said bushing, a yoke carried by said rock-shaft and having escapement-fingers adapted alternately to engage said bobbin-carrier for restraining the bobbin-carrier against rotation with said rotary hook, and operative connections with said eccentric for actuating said rock-shaft.

10. Stitch-forming mechanism for sewing ma-

chines comprising, a reciprocating needle, a rotary hook having a bobbin-carrier raceway, a rotary hook carrying shaft, a bobbin-carrier journaled in said raceway and about which bobbin-carrier the needle-thread loops are cast by said rotary hook, a rock-shaft disposed substantially parallel to said rotary-hook shaft, a bushing having an eccentric-aperture in which said rock-shaft is journaled, means providing for turning adjustment of said bushing about its longitudinal axis, a yoke carried by said rock-shaft and having escapement-fingers adapted alternately to engage said bobbin-carrier for restraining the bobbin-carrier against rotation with said rotary hook, and operative connections with said rotary hook shaft for actuating said rock-shaft.

11. Stitch-forming mechanism for sewing machines comprising, a vertically reciprocating needle, a vertical-axis rotary-hook shaft, vertically spaced bearings in which said shaft is rotatably journaled, a spiral gear carried by said shaft between said bearings, a horizontally disposed rotary-hook actuating shaft, a spiral gear carried by said rotary-hook actuating shaft and in driving engagement with the spiral gear carried by said rotary-hook shaft, a rotary hook carried by the upper end of said rotary-hook shaft and provided with a bobbin-carrier raceway, a bobbin-carrier journaled in said raceway, a vertical-axis rock-shaft disposed adjacent to said hook-shaft, a yoke carried by the upper end of said rock-shaft and having escapement-fingers adapted alternately to engage said bobbin-carrier for restraining the bobbin-carrier against rotation with the rotary hook, an eccentric carried by the lower end of said rotary-hook shaft, and means actuated by said eccentric for rocking said rock-shaft.

12. A loop-taker mechanism for sewing machines, comprising, a vertically disposed and tubular rotary-hook shaft, a rotary hook carried by the upper end of said shaft and provided with a bobbin-carrier raceway, a bobbin-carrier journaled in said raceway, an eccentric having a stem extending into the bore of said shaft from the lower end thereof, a screw extending downwardly through an aperture in the bottom wall of said rotary hook and threaded into said stem of the eccentric, means for securing said eccentric against rotation relatively to said hook-shaft, and bobbin-carrier controlling mechanism actuated by said eccentric.

WALTER MYERS.
